UNITED STATES PATENT OFFICE.

LORENZO EVANS, OF HITEMAN, IOWA.

ACETYLENE-GAS LAMP.

1,005,625.

Specification of Letters Patent.

Patented Oct. 10, 1911.

Application filed May 24, 1911. Serial No. 629,203.

To all whom it may concern:

Be it known that I, LORENZO EVANS, a citizen of the United States, residing at Hiteman, in the county of Monroe and State of Iowa, have invented new and useful Improvements in Acetylene-Gas Lamps, of which the following is a specification.

The invention relates to acetylene generators and has for an object to provide an acetylene lamp for producing light.

Among other features my device embodies a lamp adapted to employ carbid and water to produce a gas, the lamp being so arranged that when the carbid container is removed therefrom to refill the container, the lamp will still be operative to produce a light.

In a large number of acetylene lamps now in use, when the carbid contained in the main carbid container becomes exhausted, the container must be withdrawn from the lamp and refilled with carbid to produce new gas and in the meantime the light at the burner of the lamp will be extinguished so that if there is no other light present the operator will be in the dark. In my device the lamp is so arranged that a light will be produced at all times, even when the main carbid container is being refilled with carbid to generate a new gas.

Reference is to be had to the accompanying drawings constituting a part of this specification, in which similar characters of reference denote corresponding parts in all the views, and in which—

Figure 1 is a vertical sectional view of my device. Fig. 2 is a horizontal section on the line 2—2 in Fig. 1, looking in the direction of the arrow. Fig. 3 is a fragmentary sectional view of one of the water tubes and needle valve. Fig. 4 is a plan view of the lamp.

Referring more particularly to the views, I provide a body 10 having the bottom thereof recessed and threaded to receive a carbid container 11, the body 10 being provided with a cover 12 and a hook 13 for securing the body to any convenient object. A partition 14 in the body 10 divides the same to form compartments 15, 16, the compartment 15 being adapted to contain water and the compartment 16 being adapted to contain carbid and constitute an auxiliary carbid container, a cover 17 being threadedly connected to the cover 12 so that carbid can be placed in the compartment 16. A

tube 18 having apertures 19 therein is extended through the water compartment 15 with the lower end of the tube projecting into the carbid container 11, the upper end 60 of the said tube being secured to the cover 12. The lower end of the tube 18 terminates in the valve seat 20 and extending through the tube is a rod 21 having the lower end pointed to constitute a needle 65 valve 22 adapted to rest on the valve seat 20 and the upper end of the said rod is threaded for engagement with a head 23 of the tube 18, a knob 24 being secured to the outer end of the rod 21. An auxiliary 70 water tube 25, similar to the tube 18 extends from the cover 12 through the water compartment 15 and the partition 14 into the auxiliary carbid container 16, the said tube being provided at the lower end with 75 a valve seat 26 similar to the valve seat 20 and extended through the said tube is a rod 27 having the lower end pointed to form a needle valve 28 and the upper end provided with a knob 29 and threadedly engaging the tube 25, the said tube being provided with a series of apertures 30. A burner 31 extends outwardly from the body 10 and an auxiliary burner 32 extends outwardly from the compartment 16, the 85 burner 31 having an end terminating at the indented portion of the body 10 to receive gas generated in the container 11.

In the operation of my device carbid is placed in the carbid container 11 and in the auxiliary carbid container designated by the numeral 16 and water is poured into the water compartment 15. Now by turning the knob 24, the needle valve 22 will be operated, thus permitting water to flow from 95 the compartment 15 through the apertures 19 in the tube 18 and downwardly into the carbid container 11, the mixture of carbid and water being adapted to produce gas in the usual manner which pours outwardly 100 through the burner 31 where it is ignited. When the carbid in the container 11 becomes exhausted, the knob 24 is first operated to actuate the rod 21 and shut off the supply of water to the container 11 and 105 the knob 29 is then actuated to operate the rod 27 thus permitting water in the compartment 15 to flow into the auxiliary container or compartment 16 where gas will be produced by the action of the water and 110 the carbid contained in the compartment 16, the said gas being then adapted to pass out-

wardly through the burner 32 where the same is ignited. Thus it will be seen that while the carbid container 11 is being refilled a light can be produced at the burner 32 by permitting water from the compartment 15 to flow into the auxiliary carbid container of my lamp and after the carbid container has been properly refilled and connected to the body 10 the water supply to the compartment 16 can be shut off by operating the knob 29 and then by turning the knob 24 water will again flow into the carbid container 11, thus producing new gas in the said container, the said gas being adapted to flow outwardly through the burner 31.

My device is particularly adaptable for use in connection with miners' lamps, it being desirable to retain a light in these kind 20 of lamps at all times when the same are in use.

Having thus fully described the invention, what I claim as new, is:—

1. A lamp comprising a body, a carbid container for removable connection with the said body, a partition formed in the said body to constitute a water compartment and an auxiliary carbid container, burners connected with the said carbid container and 30 said auxiliary carbid container, means for

supplying water to the said carbid container and means for supplying water to the said auxiliary carbid container.

2. A lamp comprising a body, a carbid container for removable connection with the said body, a partition formed in the said body to constitute a water compartment and an auxiliary carbid container and apertured tubes extending from the said water compartment to the said carbid container and said auxiliary carbid container for supplying water thereto. 35

3. A lamp comprising a body, a carbid container for removable connection with the said body, a partition formed in the said body to constitute a water compartment and an auxiliary carbid container, means for supplying water to the said carbid container, means for supplying water to the said auxiliary carbid container, an 40 adjusting screw for controlling the supply of water to the said carbid container and a second screw for controlling the supply of water to the said auxiliary carbid container. 45

In testimony whereof I affix my signature 50 in presence of two witnesses.

LORENZO EVANS.
